CLAIM

The ornamental design for a portion of a terminal for games, as shown and described.

DESCRIPTION

FIG. 1 is a top, front and right perspective view of a portion of a terminal for games showing our new design

FIG. 2 is a top, front and left perspective view thereof;

FIG. 3 is a top plan view thereof;

FIG. 4 is a bottom plan view thereof;

FIG. 5 is a front view thereof;

FIG. 6 is a rear view thereof;

FIG. 7 is a right side view thereof;

FIG. 8 is a left side view thereof;

FIG. 9 is a top, front and left perspective view of the portion of a terminal for games thereof with a display lifted up;

FIG. 10 is a top rear and right perspective view thereof; and,

FIG. 11 is a left side view thereof.

The broken lines, which define the boundary of the claimed design form no part thereof. The broken line showings of the remainder of the terminal for games various regions thereof are for illustrative purposes only and do not form part of the claimed design.
